UNITED STATES PATENT OFFICE.

MARION RICHEY, OF DAISETTA, TEXAS.

PITMAN.

Application filed February 28, 1924. Serial No. 695,830.

To all whom it may concern:

Be it known that I, MARION RICHEY, a citizen of the United States, residing at Daisetta, in the county of Liberty and State 5 of Texas, have invented certain new and useful Improvements in a Pitman, of which the following is a specification.

This invention relates to new and useful improvements in a pitman.

10 One object of the invention is to provide a pitman, of the character described, which may be readily released from the driving crank arm whenever occasion arises making it necessary, or desirable, to disengage said pitman from said arm.

Another object of the invention is to provide a pitman which is of simple construction and may be cheaply and easily produced and which is very effective for the 20 purposes intended.

With the above and other objects in view, this invention has particular relation to certain novel features of construction, operation and arrangement of parts, an example of 25 which is given in this specification and illustrated in the accompanying drawings wherein:—

Figure 1 shows a side view of a derrick and pump associated therewith, showing the pitman connecting the walking beam to the power.

Figure 2 shows an enlarged side view of the pitman, partly in section.

Figure 3 shows one end of the pitman with the stirrup through which it is connected to the walking beam; and,

Figure 4 shows a sectional view taken on the line 4—4 of Figure 2.

In the drawings the numeral 1 designates 40 the derrick having the floor 2. The numeral 3 designates the well casing in which the pump rod 4 works. A walking beam 5 is mounted on the post 6, and one end of it is connected to the pump rod 4. Power is 45 transmitted through the belt 7 which drives the pulley 8. This pulley is mounted to rotate in a suitable frame 10 and one end of its shaft has a crank arm 11 whose free end is formed with a crank pin 12. This 50 pin is connected to the other end of the walking beam through the pitman, now to be described. This pitman has the side members 13, 13, formed of channel irons which are suitably secured together at one 55 end and bolted to said end there is the stirrup 14 which receives the corresponding end

of the walking beam. Between the other ends of the side members 13 there is secured a stationary block 15 and above it there is the 60 sliding bearing block 16 whose ends move in the channels of said side members. Guides 17, 17, depend from the respective ends of the bearing block and work in guide ways 18, 18, of the stationary block to hold said blocks in alignment. A jack screw 19 is 65 threaded through the block 15 and its upper end has a swivelling connection with the movable bearing block. This screw has an enlarged head 20 on which the block 16 rests and said head is provided with sockets 21 to 70 receive a rod by means of which the screw 19 may be turned.

The upper side of the block 16 has a concaved bearing notch 22, to receive the pin 12, and mounted upon it is the bearing cap 75 23. The ends of this cap have bearings to receive the stud bolts 24, 24, which stand up from the bearing block 16. Coil springs 25, 25, surround said stud bolts and form 80 resilient seats for the bearing cap 23, and said cap is retained against detachment by the nuts 26, 26.

While the pump is operating, under normal conditions the block 16 is seated on the stationary block 15, the nut 27 on the screw 85 19 resting also on said stationary block and sustaining part of the load.

It often happens that the belt 7 comes off of the drive pulley 8. In such case the weight of the pump rods will carry the corresponding end of the walking beam down until it is stopped by the stop 28. The pump will, of course, remain idle until the belt is replaced, and with the type of pitman now in common use, this cannot be 90 done, by a single attendant, and consequently the pump remains idle until a sufficient force is obtained to turn the pulley 8 with the weight of the pump rods thereon. In this case, with my improved type of pitman, a rod is inserted in the socket 21, and the jack screw 19 turned. This will operate to pull the corresponding end of the walking beam down, the pitman parts assuming 95 the position shown in Figure 2. The other end of the walking beam, with the pump rod, will be elevated correspondingly and when elevated a clamp 29 may be secured on the rod 4 immediately above the well tubing 3 and this clamp will now sustain the 100 weight of the pump rod and relieve the walking beam of said weight. This will 105 110

free the wrist pin 12 of the load and the pitman may be readily disconnected therefrom in the usual way and the pulley then easily turned in order to replace the thrown belt. When this is done, the pitman is reconnected to the wrist pin 12 and the jack screw turned in the other direction, to seat the bearing block 16 on the stationary block 15, and the clamp 29 removed, and pumping operations again started. This work can be done by the single attendant with very little labor and small loss of time.

What I claim is:—

1. A pitman formed of side members secured together at one end and spaced apart at the other end, a stationary anchor between said spaced ends, a jack screw threaded through said anchor, a bearing block movable lengthwise between said side members with which said jack screw has a swiveling connection, a bearing cap mounted on said block and provided with end bearings, stud bolts secured to the block and fitted through said bearings, means preventing the detachment of said bearing cap from said stud bolts, yieldable members interposed between said bearing cap and said block, said cap and block having registering notches forming a wrist pin bearing.
2. A pitman formed with side members secured together at one end, a stirrup fastened to said end, the other ends of said side members being spaced apart, an anchor secured between said spaced ends, a jack screw threaded through said anchor, a bearing block between said side members and longitudinally movable with respect thereto, guides adapted to hold said block in alignment with said anchor, said jack screw forming a support for said block, a bearing cap formed with end bearings, stud bolts fixed to said block and working through said

bearings, nuts threaded onto said stud bolts and holding said cap against detachment, said cap and block having registering notches forming a wrist pin bearing.

3. A pitman having spaced side members, a stationary anchor between said side members at one end, a jack screw having a threaded connection with said anchor, a bearing block movable lengthwise between said side members with which said jack screw has a swiveling connection, a lock nut on the jack screw adapted to abut against said anchor, a bearing cap mounted on said block, means preventing the detachment of said bearing cap from said block, said means also constituting a guide for holding said cap in alignment with said block, said cap and block having registering notches forming a wrist-pin bearing.

4. A pitman having spaced side members, a stationary anchor between said side members at one end, a jack screw having a threaded connection with said anchor, a bearing block movable lengthwise between said side members with which said jack screw has an operative connection, a bearing cap mounted on said block, means preventing the detachment of said bearing cap from said block, said means also constituting a guide for holding said cap in alignment with said block, said cap and block having registering notches forming a wrist-pin bearing, and yieldable means interposed between said bearing block and cap.

In testimony whereof I have signed my name to this specification in the presence of two subscribing witnesses.

MARION RICHEY.
